PULSATION DAMPER

Harry Gluck, Munhall, and Daniel J. Snyder,
Edgewood, Pa.

Application November 16, 1942, Serial No. 465,788

2 Claims. (Cl. 138—40)

This invention relates to pulsation dampers and more particularly to such dampers that are used for preventing pulsations of a stack draft recorder.

In the gaging and recording of pressures, pulsation in pressure is one of the main sources of trouble. The rapid changes in pressure interfere with the proper recording and gaging of pressure and in some instances the change may be so great that the gage and/or recorder are damaged thereby. When a recorder is used it is often impossible to determine the operating conditions therefrom.

The former practice of pulsation restriction was to manually set a needle valve to strangle the pulsation to an instrument. This required constant watching and adjustment to get the desired dampening, thus increasing labor costs. Often, due to improper setting of the needle valve and laxity of the attendant, pulsations became so severe that the instrument element was damaged to such an extent that it had to be repaired or replaced. Usually the setting will be too little or too much, so that a good record is not obtained.

To our knowledge, the only other instrument used for pulsation control is a damper having spiral constricting tubes. If these become clogged with dirt, or are damaged in any way, the damper must be completely replaced. If it is desired to decrease or increase the dampening effect, another damper must be substituted.

It is an object of this invention to make a damper which can be easily cleaned and which has a replaceable dampening unit.

Another object is to obtain a clear recorder chart which can be easily planimetered.

Still another object is to provide for gage adjustment without breaking any of the pipe connections.

A further object is to provide a safety tap on the damper to protect the gage against sudden line surges.

These and other objects will be apparent from the following description and drawings in which Figure 1 is a layout of an installation of the pulsation damper;

Figure 2 is a cross-sectional view of the pulsation damper;

Figure 3 is an end view of the removable cartridge;

Figure 4 is a reproduction of a draft gage recorder chart obtained without using our pulsation damper; and

Figure 5 is a reproduction of a draft gage re-

corder chart obtained while using our pulsation damper.

Referring more particularly to the drawings, reference numeral 1 indicates a stack draft recorder which is to be protected by our pulsation damper. This recorder is connected to the stack by means of piping 2, the pulsation damper 3 and the piping 4. A needle valve 5 in the line 4 acts as a shut-off valve.

As best shown in Figure 2, the pulsation damper consists of a body 6 having a threaded connection 7 for connection to the inlet piping 4 and a threaded connection 8 for connection to the outlet piping 2. The body 6 is hollow and has a threaded connection 9 for receiving a removable cartridge 10 which supports a plurality of capillary tubes 11. This cartridge may be replaced by another cartridge having different resistance to flow. If it is desired to use the same cartridge to obtain a different resistance, one or more of the tubes 11 may be plugged. A groove 12 in the cartridge enables it to be easily removed by means of a screw driver. As the pressure in the line varies the pen of the recorder will vibrate, giving a blurred effect as shown in Figure 4. The pulsation damper by means of the restriction of flow in the capillary tubes 11 prevents the rapid fluctuation of the recorder pen 13. When it is desired to have greater restriction to flow, we may decrease the number of tubes or increase their length and/or decrease their diameter. By varying these three factors any desired restriction to flow may be obtained.

If the fluid in the line is dirty, the tubes 11 may be protected by inserting a strainer on the inlet side of the tubes. If the tubes 11 become dirty, they may be cleaned by means of a wire. Such cleaning is not possible when using a spiral pulsation damper.

In previous installations, if it were desired to calibrate the instrument, it was necessary to break the connections in the line. To overcome this, a pressure tight plug 14 is screw-threaded into the body 6. This plug contains a threaded bore 15, to which a pet-cock 16 is connected. The calibrating instrument may be connected to the pet-cock and therefore it is not necessary to break any connection in the line.

To protect the instrument from damage on account of sudden surges in pressure, there is a tap 17 in the body or the end opposite plug 14. To this is connected a safety seal 18. In case the line impulse should go over the maximum recorder element pressure, the safety connection for the

element will allow the seal to be blown out, thus bleeding the line impulse direct to the atmosphere. A safety pop-off valve or other safety device may be used in place of the U tube.

While the invention has been disclosed as applied to a stack draft recorder, it may be applied to any recorder or gage using a fluid medium such as air, gas, oil, water, and steam, as long as the medium is not too viscous to flow through the capillary tubes. The medium used will determine the kind of material to be used in constructing the pulsation damper. Ordinarily the damper is made of non-corrodible material and the strength is varied in accordance with the pressure to be gaged.

Briefly the operation of the damper is as follows:

The needle valve 5 operates as a shut-off valve. When pulsations occur, they are damped as they are transmitted through the capillary tubes, thus increasing or decreasing the pressure on the instrument side gradually instead of suddenly, until equal pressures are again achieved. This allows the element in the recorder to oscillate correctly at each pressure change, rather than recording extremely high or low due to the pulsations. This achieves our purpose of obtaining readable and accurate charts, which may be readily planimetered as is apparent from an inspection of the chart shown in Figure 5. This chart plainly shows the difference in checker resistance of the open hearth furnace and shows all furnace reversals. Advantages of the pulsation damper are apparent from a comparison of Figures 4 and 5. The readings obtained when using the damper are clear and accurate while those obtained without it are blurred and the pulsations are recorded, giving extremely high and low pressures. Hand

adjustment by means of the needle valve improves the readings, but this requires constant attention and the readings are not as clear as those obtained when using the damper. In case the line impulse goes over the maximum recorder element pressure, the safety connection on the damper enables the line impulse to bleed directly to the atmosphere. When it is desired to calibrate the instrument, it is only necessary to close shut-off valve 5, connect pet-cock 16 to the calibrating instrument and open pet-cock 16. When cleaning or replacing the removable cartridge 10, valve 5 is closed, the plug 14 is removed, and the cartridge unscrewed from the body.

While a particular modification of our invention has been disclosed and described, it will be apparent that we do not wish to be limited exactly thereto, since various modifications may be made while remaining within the scope of the following claims.

We claim:

1. A pulsation damper comprising an elongated hollow body open at one end, an inlet at one end of the body connected to a source of fluid pressure, an outlet at the other end of the body connected to a pressure gage, a removable cartridge within the body located between the inlet and outlet, a plurality of capillary tubes extending lengthwise of the body and supported by the cartridge, and a plug for closing the open end of said body, said plug having a diameter of sufficient size to permit removal of said cartridge from said body.

2. A pulsation damper as defined in claim 1 having a pressure release device attached to the body between the inlet and removable cartridge.

HARRY GLUCK.

DANIEL J. SNYDER.
